UNITED STATES PATENT OFFICE.

ALBERT M. KRUEGER, OF CLEVELAND, OHIO.

ROTARY ENGINE.

SPECIFICATION forming part of Letters Patent No. 773,649, dated November 1, 1904.

Application filed March 31, 1902. Serial No. 100,814. (No model.)

To all whom it may concern:

Be it known that I, ALBERT M. KRUEGER, a citizen of the United States of America, residing at Cleveland, in the county of Cuyahoga and State of Ohio, have invented certain new and useful Improvements in Rotary Engines; and I hereby declare the following to be a full, clear, and exact description of the invention, such as will enable others skilled in the art to 10 which it pertains to make and use the same.

This invention relates to improvements in rotary engines, and especially to that class employing compressed air, steam, and analogous gases as a source of energy or propelling me- 15

The object of this invention is to provide an engine of this class which will be simple and compact in construction and economical and powerful when in action.

20 With this object in view my invention comprises a new and improved piston, new and improved means for equalizing the wear on the surface of the piston, new and improved means for automatically compensating for the 25 wear on the surface of the piston and steam chamber, and new and improved valve-operating mechanism.

My invention also consists of the new and original features of construction and combination of parts, as illustrated in the drawings 30 and hereinafter described in the specification and pointed out in the claims.

In carrying out my invention I provide a cylindrical piston-chamber in which I arrange 35 a cam-shaped piston which extends longitudinally of the piston-chamber. The piston is secured on a shaft which is mounted centrally in the piston-chamber, and the piston is so suspended thereon that only a small part of the 40 surface thereof will touch the interior surface of the piston-chamber during a complete revolution of the piston. In the side of the cylinder I form an opening which extends the full length of the cylinder, and in this opening I arrange an abutment which extends into the piston-chamber a sufficient distance to 45 come into contact with the surface of the piston. This abutment is supported on a lever-arm which is pivotally mounted at one side of 50 the cylinder. This arrangement reduces the

friction between the abutment and the edges of the opening in the cylinder to a minimum, as the abutment is supported independently of the cylinder, and the abutment can be moved easily in and out when under steam-pressure, 55 and it will not bind against the sides of the opening. Springs are provided which exert a constant pressure against the abutment, so as to hold it in contact with the surface of the piston during the complete revolution of the 60 piston, and as the piston revolves the abutment will move in and out following the contour of the piston. A steam-inlet is formed in the cylinder above the opening for the abutment and is provided with a valve which is 65 operatively connected with the piston. An exhaust is formed at the same side of the cylinder below the opening for the abutment. When the steam is first admitted to the piston-chamber, it fills the triangular space be- 70 tween the abutment and the adjacent surfaces of the cylinder and piston. The pressure of the steam causes the piston to revolve, enlarging the steam-space and exposing a greater portion of the surface of the piston to the ac- 75 tion of the steam. As the piston revolves it opens and closes the steam-valve through its operative connection therewith, and the abutment moves in and out under the combined action of the piston and springs. 80

In the accompanying drawings, Figure I is a vertical section of my improved rotary engine. Fig. II is a section on lines II II, Fig. I, showing a hatching across the steam-inlet. Fig. III is a section on lines III III, Fig. I, 85 showing a similar hatching across the exhaust-port. Fig. IV is a section on lines IV IV, Fig. I. Fig. V is a section on lines V V, Fig. I, showing the construction of the abutment. Fig. VI is a section on lines VI VI, Fig. I, 90 for the same purpose.

Again referring to the drawings, a represents the cylinder of my engine, which is provided with the end pieces a^2 and a^3 , removably secured thereto by means of bolts a^4 . The interior surface of the cylinder is slightly beveled at both ends. At each end of the cylinder are arranged packing-rings a^5 and a^6 . Each ring is triangular in cross-section and is preferably split, so that it can be sprung into po- 95 100

sition and leave a small space between its ends, so as to allow for adjustment. Screws a^6 are provided, which pass through the respective end plates and engage the packing-rings a^5 . 5 These screws a^6 prevent the packing-rings from turning and also serve to adjust them to compensate for the wear on their surfaces.

Openings a^7 and a^8 , respectively, are formed in the sides of the cylinder and constitute the 10 steam inlet and exhaust port. Across each opening is arranged a hatching formed of a series of bars a^9 and a^{10} , respectively, arranged parallel with each other and at an angle to the top and bottom edges of the respective 15 openings, and the arrangement of the bars is such that the bottom edge of one bar is in a vertical line with the top edge of the adjacent bar. The object of the hatching is to form a stop across the respective openings, and the 20 peculiar arrangement of the bars equalizes the wear on the surface of the portion of the piston which comes into contact therewith and prevents it from becoming grooved, as there 25 is no part of said surface but what will come into contact with one of the bars.

Bearings are formed centrally in the respective end plates a^2 and a^3 of the cylinder, and in these bearings is mounted a shaft b , which is arranged to extend a short distance beyond 30 the said plates. On this shaft is mounted a cam-shaped body b' , which constitutes the piston. The cam-shaped body or piston b' is so suspended on the shaft b that it touches the interior surface of the cylinder only at one 35 point. On each end of the piston is secured an annular plate b^2 and b^3 , respectively, of equal diameter with the interior diameter of the cylinder. The edges of the outer surfaces of the annular plates b^2 and b^3 are beveled 40 corresponding to the bevel on the triangular packing-rings a^5 . Between the end plates a^2 and a^3 and the plates b^2 and b^3 are preferably arranged washers b^4 . The object of these 45 plates b^2 and b^3 is to provide a perfectly steam-tight packing between the respective ends of the piston and the cylinder, thus preventing any escape of steam around the bearings of the piston-shaft b . The respective packing-rings a^5 and a^6 , as before indicated, can be 50 adjusted so that they will always be in close contact with the edges of the respective plates b^2 and b^3 .

In the surface of the piston where it touches the interior surface of the cylinder is formed 55 a groove b^5 , which extends the full length of the piston. In this groove is mounted a plate b^6 , preferably by pivoting or hinging it at one side by means of a pin b^7 . Underneath the plate b^6 is arranged a bow-spring b^8 , which 60 presses the plate b^6 against the interior surface of the cylinder. This plate b^6 forms a packing which automatically adjusts itself to compensate for the wear on the piston and the interior surface of the cylinder.

65 Between the steam-supply pipe a^{11} and the

opening a^7 in the cylinder and in close proximity to said opening a^7 is arranged a balanced rotary valve comprising a valve-casing c and rotary valve c' . The valve-casing is recessed, as at c^5 , to provide a steam-space at the back 70 of the valve to balance the pressure on the valve of the steam flowing through the valve. The steam-supply pipe is forked to supply steam above and below the valve. The valve-stem c^2 extends beyond the casing, and on the 75 end thereof is mounted an arm c^3 . A pin c^4 is secured in the end of the arm c^3 . On the outer face of the end plate a^3 of the cylinder above the shaft c is secured a pin d , on which is mounted a lever d' . In the end of the longer 80 arm e is formed a slot d^2 , adapted to receive the pin c^4 on the end of the arm c^3 , secured to the valve-stem c^2 . In the end of the shorter arm of the lever is secured a pin d^3 , on which is mounted a roller d^4 . On the end of the 85 shaft b without the cylinder a is secured a cam e so arranged that during a portion of the revolution of the shaft it will come into contact with the roller d^4 on the lever d' . A spring d^5 is secured to the lever d' , so that the 90 lever in its normal position will hold the valve closed and the roller d^4 against the surface of the cam. As the shaft b turns the cam e lifts the short arm of the lever d' and depresses the longer arm, causing a rotation of the valve-stem in the direction to open the valve. When the cam e leaves the roller d^4 , the spring d^5 causes the lever d' to assume its normal position, closing the valve.

At the side of the cylinder is mounted my 100 improved abutment. This abutment comprises two supporting-arms f and f' , which are pivotally mounted on a shaft f^2 . On top of the arms is mounted a box or frame consisting of a bottom plate f^3 , which extends the 105 full length of the opening a^4 , a top plate f^4 of equal length, but of greater width than the plate f^3 , so that the front edge thereof extends beyond the front edge of the plate f^3 , a back plate f^5 , and vertical plates f^6 for bracing and securing the top and bottom plates together. In this frame are arranged three flat plates g , g' , and g^2 , equal in length to the top and bottom plates f^3 and f^4 . Slots g^3 , g^4 , and g^5 are formed in the respective plates g , 110 g' , and g^2 to accommodate the vertical plates and to allow them to move freely in and out in the frame. In each plate g , g' , and g^2 are secured pins g^6 , g^7 , and g^8 , which project beyond the back of the frame through openings 115 formed in the plate f^5 . Under the respective plates g , g' , and g^2 are arranged packing-plates g^9 , g^{10} , and g^{11} . Slots are formed in these plates, and in the slots are arranged projections which engage projections or shoulders 120 f^{11} , formed on the vertical plates f^6 , so as to lock them in the frame and prevent them from moving forward when the plates g , g' , and g^2 are advanced.

125 Springs f^7 are mounted in proximity to the 130

abutment and are arranged to exert a constant pressure against the frame of the abutment, so as to hold the plate f^4 in contact with the surface of the piston. Similar 5 springs f^8 and f^9 and f^{10} are secured to the arms of the abutment and press against the pins in the ends of the plates g , g' , and g'' , forcing them outwardly in the frame of the abutment and against the face of the piston 10 b' . A packing-plate h is mounted above the plates f^3 . Screws h' are mounted in the casting above the plate h and are arranged to engage with the said plate, so that it may be adjusted to take up the wear between the two 15 surfaces. A washer h^3 of corrugated copper or other soft material is arranged between the end of the plate h and the wall of the cylinder a .

What I claim is—

1. In a rotary engine, a cylinder, steam- 20 ports formed in the said cylinder and hatchings arranged over said ports, comprising a series of parallel bars arranged at an angle to the top and bottom edges of the respective ports and the arrangement of the said bars is such that the bottom edge of one bar is in a 25 vertical line with the top edge of the adjacent bar, substantially as described and for the purpose set forth.

2. A rotary engine comprising a cylindrical 30 casing, end plates secured to said casing, port-holes formed in said casing, a shaft mounted centrally in bearings formed in said end plates, a piston keyed to said shaft, a groove formed in said piston, a plate mounted in said groove, 35 a spring arranged beneath said plate and adapted to hold said plate against the interior surface of the said casing, and diagonally-disposed bars arranged across said port-holes, substantially as and for the purpose set forth.

40 3. A rotary engine comprising a cylindrical casing, hatching arranged across said port-holes, a shaft mounted centrally in bearings formed in said end plates, a piston keyed to said shaft, said piston comprising a cam-shaped body arranged so that only a portion 45 of its surface will be in contact with the interior of the said casing during a revolution of said piston, a groove formed in the said piston at the point where the said piston comes in contact with the interior surface of the said casing, a plate mounted in said groove, a 50 spring arranged beneath said plate and adapted to hold said plate against the interior of said casing, annular plates arranged at the respective ends of the piston, and packing-rings 55 arranged between the said annular plates and the end plates of the said casing, substantially as described and for the purpose set forth.

4. In a rotary engine, the combination of a 60 casing, end plates secured to said casing, a steam-inlet formed in said casing, a rotary valve arranged to control the admission of steam through the said inlet, a shaft mounted centrally in bearings formed in said end plates, 65 a piston keyed to said shaft, an abutment ar-

ranged to move in and out according to the movement of the said piston, a lever pivotally secured on the outer surface of one of said end plates and having one of its ends operatively connected with the stem of the said rotary valve, a roller mounted on the opposite end of the said lever, a spring secured to the said lever for holding the same in its normal position, and a cam mounted on the outer end of said piston-shaft and arranged to come in contact with the said roller during a part of the revolution of the said piston, substantially as described and for the purpose set forth. 70 75

5. In a rotary engine, the combination of a casing, end plates secured to said casing, port-holes arranged in said casing, a shaft mounted centrally in bearings formed in said plates, a piston keyed to said shaft, said piston comprising a cam-shaped body extending the full length of the said casing, and arranged so 80 that only a portion of the surface will be in contact with the interior surface of the said casing during a complete revolution of the said piston, and an abutment arranged in an opening in the said casing, said abutment comprising supports pivotally mounted without 85 said casing plates arranged on top of said supports and adapted to extend through the opening in said casing and means for exerting a yielding pressure on said supports so as to hold 90 said plates in contact with the surface of said piston, substantially as described and for the purpose set forth.

6. In a rotary engine, the combination with a casing, end plates secured to said casing, port-holes arranged in said casing, a shaft mounted centrally in bearings formed in the said end plates, a piston keyed on said shaft, said piston comprising a cam-shaped body extending the full length of the said casing and 100 arranged so that only a portion of its surface will be in contact with the interior surface of the said casing during a complete revolution of the said piston, an abutment arranged in an opening in said casing, said abutment comprising supports pivotally mounted without 105 said casing, a frame mounted on top of said supports, plates arranged to slide in and out of said frame, springs arranged to exert a constant pressure on said supports and springs 110 arranged to exert a constant pressure on the respective plates, substantially as described and for the purpose set forth.

7. In a rotary engine, the combination of a casing, end plates secured to said casing, port-holes arranged in the said casing, a shaft mounted centrally in bearings formed in said plates, a piston keyed to said shaft, said piston comprising a cam-shaped body extending the full length of the said casing, and arranged 120 so that only a portion of the surface will be in contact with the interior of the said casing during a complete revolution of the said piston, and an abutment arranged in an opening in said casing, said abutment comprising sup- 125 130

ports pivotally mounted without said casing, plates rigidly secured to said supports, movable plates mounted between the rigid plates, packing-plates arranged between the respective plates, and springs arranged to exert a constant pressure on the respective plates for holding them against the surface of the piston, and packing devices arranged at the top and side of the said abutment, substantially as and for the purpose set forth.

8. In a rotary engine, a steam-cylinder, a cam-shaped piston operatively mounted in said cylinder, port-holes formed in cylinder, an opening formed in the side of said cylinder, a support pivotally mounted without said cyl-

inder, an abutment mounted on said support and arranged to extend through the said opening in said cylinder and come in contact with the said piston and a spring arranged to hold said abutment against said piston, substantially as described. 20

In testimony whereof I sign the foregoing specification, in the presence of two witnesses, this 21st day of March, 1902, at Cleveland, Ohio.

ALBERT M. KRUEGER.
